(57) **CLAIM**

The ornamental design for a top sizer clip, as shown and described.

DESCRIPTION

FIG. 1 is a front perspective view of a top sizer clip showing my new design;

FIG. 2 is a front elevation view thereof, the rear elevation view being a mirror image thereof;

FIG. 3 is a left side elevational view thereof, the right side elevational view being a mirror image;

FIG. 4 is a top plan view thereof; and,

FIG. 5 is a bottom plan view thereof.

The broken lines shown in the drawing disclosure are for illustrative purposes only and form no part of the claimed design.
